United States Patent Office.

SAMUEL SMITH, OF YOHOGANY, PENNSYLVANIA.

Letters Patent No. 97,820, dated December 14, 1869.

IMPROVEMENT IN CHURNS.

The Schedule referred to in these Letters Patent and making part of the same.

To all whom it may concern:

Be it known that I, SAMUEL SMITH, of Yohogany, Westmoreland county, and State of Pennsylvania, have invented a new and useful Improvement in Churns; and I hereby declare the following to be a full and complete description of the same, reference being had to the accompanying drawings, in which—

Figure 1 is a vertical longitudinal section;

Figure 2 is a plan;

Figure 3 is a vertical cross-section;

Figure 4 is an elevation of one of the racks detached; and

Figure 5 is a view of one of the holding-strips detached.

Like letters refer to the same parts in all the figures.

To enable others skilled in the art to make and use my invention, I will proceed to describe its construction and operation.

The nature of my invention is to so arrange the internal parts of the churn as to create the greatest number of counter-currents in the milk, and to break up and derange all tendency to continuous or circular currents, and, at the same time, to cause the butter to collect in one end of the churn as fast as formed, at the same time keeping in view the greatest simplicity and economy in the structure of the churn, and the necessity of its being readily and quickly taken apart for cleaning and purifying, and put together again, so as, at all times, to be easily kept in a cleanly and sweet condition, and to be within the ready comprehension and control of ordinary dairy-maids and domestics.

The body of the churn consists of a strong watertight rectangular box or case, L, of about the proportions shown, and of size according to the capacity required.

Lengthwise through the longest axis of the box, passes a revolving shaft, H, provided with two spiral series of dashers in the form of oblique paddles G G, the faces of the dashers being set at an angle of from thirty to forty-five degrees with the axis of the shaft H.

The shaft H is connected, at one end, by a simple clutch, of any ordinary construction, with the crank-head K of the crank F, and the other end is held in place by, and revolves upon, a centre point upon a thumb-screw, J.

About midway between the shaft H and the sides of the churn, on each side of the shaft, is placed a ver-

tical rack, composed of horizontal top and bottom pieces A E, and slats B B B, extending the whole length of the churn.

The vertical slats B B correspond with the sets of dashers on the shaft, in such order that a pair of opposite dashers revolves between each pair of slats on both sides of the shaft, the sweep of the dashers extending through and beyond the plane of the rack.

The racks are held securely in place, at the top, by means of the notched cross-strips C C, fig. 5, fitting over and into corresponding notches in the end of top pieces A, fig. 4. The pieces E maintain the bottom of the rack in place by their bearing against the sides of the churn, they being made of proper width to just fill the space between the slats and the walls of the churn, as seen in fig. 3.

A close-fitting cover, D, fig. 1, is indicated in dotted outline.

The operation of the churn is obvious, being filled with milk or cream to a proper height, the shaft H is briskly rotated by means of crank F, or otherwise, and the combined action of the oblique, spirally-arranged dashers, and the interlocking slats is such as to produce the most perfect agitation of the milk, all tendency to form currents being effectually prevented, and the butter is therefore produced in the shortest possible time.

After churning it is absolutely necessary to take the churn apart for the purpose of thoroughly cleansing and purifying it, a fact well known to dairymen.

To do this, it is only necessary to slacken the set-screw J, which releases the shaft H. The racks A being retained in place by the strips C without fastenings, the whole internal parts of the churn may then be readily lifted out.

Having thus described my invention,

What I claim as new, and desire to secure by Letters Patent, is—

The shaft H, provided with revolving dashers G G, in combination with the racks B B, arranged upon each side of the shaft, and extending from the bottom to the top of the churn-box A, and the notched cross-bars C C, all constructed and operating as and for the purpose set forth.

SAMUEL SMITH.
